JOUNCING FOOT TOY

Norman T. Mills, 42 Clinton Ave., Bridgeport, Conn.

Filed Feb. 17, 1961, Ser. No. 63,979

Term of patent 14 years

(Cl. D34—5)

Fig. 1.

Fig. 2.

FIG. 1 is a perspective view of a jouncing foot toy showing my new design, and looking from the front, and FIG. 2 is a rear perspective view.

I claim:

The ornamental design for a jouncing foot toy, substantially as shown.
